CLAIM

The ornamental design for a storage box primarily for computer discs, as shown.

DESCRIPTION

FIG. 1 is a perspective view of a storage box primarily for computer disks, showing our new design;

FIG. 2 is a perspective view thereof in the open position, with the lid on the left and the base on the right;

FIG. 3 is a left side elevation of FIG. 1;

FIG. 4 is a top plan view thereof;

FIG. 5 is a front end view elevational view thereof;

FIG. 6 is a right side elevational view thereof;

FIG. 7 is a bottom plan view thereof;

FIG. 8 is a rear elevational view thereof; and,

FIG. 9 is a plan view of the box in the open position, with the base on top and the lid at the bottom.
